UNITED STATES PATENT OFFICE.

HOWARD H. HERING, OF MANSFIELD, OHIO, ASSIGNOR TO NORTH AMERICAN WATCH COMPANY.

DESIGN FOR A WATCHCASE.

Application filed May 19, 1924. Serial No. 9,659. Term of patent 7 years.

To all whom it may concern:

Be it known that I, HOWARD H. HERING, a citizen of the United States, residing at Mansfield, in the county of Richland and State of Ohio, have invented a new, original, and ornamental Design for a Watchcase, of which the following is a specification, reference being had to the accompanying drawing, forming part thereof, in which—

Fig. 1 is a front view of the watch case,
Fig. 2 is a side elevation.

I claim:

The ornamental design for a watchcase as shown.

H. H. HERING.
